STANISLAUS KUCHARSKI, OF CHARLOTTENBURG, NEAR BERLIN, GERMANY,
ASSIGNOR TO RICHARD A. HANSEMANN, OF BERLIN, GERMANY.

MOTOR MECHANISM FOR OPERATING TELAUTOGRAPHS.

1,418,657.

Specification of Letters Patent. Patented June 6, 1922.

Application filed October 1, 1919. Serial No. 327,830.

To all whom it may concern:

Be it known that I, STANISLAUS KUCHARSKI, a citizen of Germany, residing at and whose post-office address is Charlottenburg, 5 near Berlin, Dernburgstrasse 45, Germany, have invented certain new and useful Improvements in Motor Mechanism for Operating Telautographs (for which I have filed an application in Germany, Sept. 19, 1918); 10 and I do hereby declare the following to be a full, clear, and exact description of the invention, such as will enable others skilled in the art to which it appertains to make and use the same.

15 This invention relates to improvements in Gray's telautographic instruments in which the movements of the pencil or stylus in the sending instrument are transmitted to the receiving instrument with the aid of electric current impulses which, by means of suitable electromagnets, impart corresponding step-by-step movements to the pencil in the receiving instrument. This is accomplished with the aid of an escapement wheel to 20 which a tendency to rotate is permanently imparted by a constant source of power, this wheel being alternately released and stopped by pallets controlled by the stepping electromagnet.

25 A known arrangement consists in the power that turns the escapement wheel, when released by the pallets, being stored up in a spring which continually tends to urge on the wheel like the main spring of a clock. In this known arrangement the 30 said permanent power moves and accelerates, not only the escapement wheel at the moment it is released, but also all the parts connected to it such as the transmission 35 wheels, escapement wheel shaft, and the writing mechanism of the receiving instrument which is driven by this shaft. In cases where the current impulses are received in very rapid succession the said arrangement does not enable the parts to be accelerated as rapidly as desired, so that the 40 escapement wheel of the receiver does not always keep pace with the current impulses with the required accuracy.

45 The object of the present invention is to provide an arrangement by which the escapement in the receiver can easily and accurately keep pace with the series of impulses even if they are sent at a very rapid 50 rate. This is accomplished by coupling the

escapement wheel to its shaft by springs that are kept tensioned by the permanently active driving power, and operation of which is such that they turn the escapement wheel immediately it is released, the shaft and the 60 other parts in engagement with it being caused to follow the wheel by the said permanently active driving power.

A manner of carrying out the invention is illustrated in the drawing in which 65

Fig. 1 represents a top view and
Fig. 2 a cross section on the line A—B of
Fig. 1 viewed from the right.

The escapement wheel *b* is loosely mounted on the shaft *a* between two discs *d*, *d*¹ 70 which serve to guide the escapement wheel and which are surrounded by springs *c*, *c*¹. The one end of each spring *c*, *c*¹ is fixed to its hub *d*, *d*¹ whilst the other end is attached to pins in the escapement wheel. 75 These pins project into notches *e* in the discs *d*, *d*¹ (Fig. 2). The escapement wheel is controlled in the ordinary manner by a pallet *f* which is oscillated by an electromagnet *h*, and if necessary with the aid of a spring. 80 The controlling movements of the shaft *a* are transferred in a known manner by a toothed wheel *g* to the rod *i* that controls the writing mechanism of the receiver. The shaft *a* is also under the influence of a power 85 which is permanently exerted in the case illustrated by a spring enclosed in a box *k* through intermediate gear *l*.

The device operates in the following manner:

90 Suppose that the driving power tends to turn the shaft *a* and the discs *d*, *d*¹ fixed on the shaft, as shewn in Fig. 2, in a counter clockwise direction. This rotary motion can only continue until the sides of 95 the notches *e* of the discs *d*, *d*¹ strike against the pins by which the springs *c*, *c*¹ are attached to the escapement wheel. In this manner the springs *c*, *c*¹ are tensioned. If the pallet *f* is now moved by a current impulse so as to release the escapement wheel, the springs *c*, *c*¹ immediately urge the escapement wheel one step forward, whereupon the shaft *a* with discs *d*, *d*¹ is rotated by the permanent driving power until the 100 sides of the notches *e* strike afresh against the pins to which the springs *c*, *c*¹ are attached, the pins thus limiting the movement of the shaft. The springs *c*, *c*¹ will then be tensioned again. At the same time the 105 110

escapement wheel will again be detained by the pallet *f*. It is thus seen that at each current impulse only the escapement wheel itself is moved at first, this wheel being in no wise encumbered by any other parts. The other parts are thus given time to move at a speed corresponding to their own inertia. The small differences of time between the movements of the escapement wheel and those of the rod controlling the writing mechanism have no deleterious effect on the writing in the receiver because these differences are balanced in a few fractions of a second. The springs or the means of attaching them are made to act as stops in order to prevent the escapement wheel from lagging too far behind or moving too far ahead of the shaft.

I claim:

20 1. In a telautograph of the Gray type, a shaft, a source of power permanently tending to turn said shaft, an escapement wheel loosely mounted on the shaft, a spring coupling the escapement wheel to the shaft, 25 a pallet detaining the escapement wheel

so as to enable the said source of power to tension the said spring, and an electromagnet for moving the said pallet and releasing the escapement wheel.

2. In a telautograph of the Gray type, a 30 shaft, a source of power permanently tending to turn the said shaft, an escapement wheel loosely mounted on the shaft, a coupling spring attached at one end to the escapement wheel and at the other end to 35 the shaft, a pallet detaining the escapement wheel so as to enable the said source of power to tension the said spring, the said coupling spring being adapted to operate also as a stop-member for limiting the rotary 40 movement of the escapement wheel relative to the shaft, and an electromagnet for moving the said pallet and releasing the escapement wheel.

In testimony whereof I affix my signature, 45 in presence of two witnesses.

STANISLAUS KUCHARSKI.
